UNITED STATES PATENT OFFICE.

WILLIAM R. KUEHNEL, OF CHICAGO, ILLINOIS.

WINDOW-CLEANING DEVICE.

1,293,125.

Specification of Letters Patent.

Patented Feb. 4, 1919.

Application filed November 24, 1917. Serial No. 203,703.

To all whom it may concern:

Be it known that I, WILLIAM R. KUEHNEL, a citizen of the United States, residing at Chicago, in the county of Cook and State 5 of Illinois, have invented new and useful Improvements in Window-Cleaning Devices, of which the following is a specification.

This invention relates to a window cleaning device designed particularly for use on 10 street and railway cars, locomotives, boats, automobiles, etc., for removing from the outer surface of the window pane frost or other moisture deposits, dust or any other 15 substance tending to obscure a clear view through the glass.

The object of the invention is to provide 20 an improved window cleaning device of the kind mounted upon the outside of the window for movement across the glass pane or panel, and which embodies improved means for operating the same from the interior of the vehicle without the necessity of opening the window.

25 A further object of the invention is to provide a window cleaning device of the character described which is simple of construction, reliable and efficient in operation, and which embodies means for permitting 30 the window sash to be readily opened and closed without interference from the operating mechanism of the cleaner.

The invention consists of the features of 35 construction, combination and arrangement of parts, hereinafter fully described and claimed, reference being had to the accompanying drawing, in which:—

Figure 1 is a view in elevation looking 40 toward the exterior of a window, showing my improved cleaner mounted in operative position and showing the cleaner at one of its extreme limits of movement.

Fig. 2 is a view in elevation looking 45 toward the interior of the window, the cleaner appearing in dotted lines.

Fig. 3 is a vertical section on the line 3—3 of Fig. 1.

Fig. 4 is a vertical section on the line 4—4 of Fig. 1.

50 Referring to the drawing, 1 designates a window sash, comprising a frame of suitable form inclosing a glass pane or panel 2. This sash may be slidably mounted for opening and closing movements in a frame 3 of 55 any ordinary construction. It is to be understood that the sash and frame may

vary in construction according to its use upon a street or railway car, boat cabinet, locomotive cab, or any other vehicle, to suit different requirements of service. 60

The cleaner 4 comprises an elongated head 5, extending vertically upon the outer side of the panel or glass pane 2 and provided upon its inner face with a groove in which is seated and secured a strip of cleaning 65 material 6, such as felt, rubber, or any other suitable material. The device thus forms a wiper adapted to be reciprocated or oscillated transversely across the pane 2 from side to side thereof, to remove therefrom 70 any deposits thereon tending to obscure clear vision through the pane.

The head 5 is pivotally mounted upon a pivot member 7 projecting at right angles from the upper free end of an arm 8. The 75 arm 8 extends vertically and is fixed at its lower end to the outer end of a rock shaft 9, whereby on reverse rocking movements of the shaft from right to left, and vice versa, the cleaner will be reciprocated or oscillated 80 across the pane to remove therefrom any deposits thereon. The cleaner is adapted by gravity to assume a direct vertical position when the arm 8 is in a direct vertical position parallel with a line passing through the 85 center of the panel 2, and is adapted to substantially maintain this position as it is moved across the pane, varied to some extent by the resistance of the pane to its movements by its frictional contact therewith. 90

As the arm 8 swings to the right or left from a central position it necessarily takes an inclined position, but the cleaner through its pivotal mounting swings thereon to normally maintain a vertical position. To limit and 95 control this swinging movement, a cord or other flexible connection 10 is provided between the lower end of the cleaner and the arm 8, which connection serves to prevent the cleaner from swinging laterally beyond a 100 limited extent in either direction, due to the varying resistance to its movement which may occur at different points along the surface of the pane.

The shaft 9 extends through and is journaled in the bottom rail of the sash 1 and its inner end projects beyond the inner face of the sash and is formed with an angular socket 11 to receive an angular projection 12 upon an actuating handle or crank 13, 110 whereby the shaft may be rocked or oscillated to actuate the cleaner. It will thus

be apparent that the cleaner may be operated from the inside of the window to remove deposits from the outer side of the pane without the necessity of opening the window.

The crank or actuating device 18 is mounted for oscillation or rotation upon a bracket 14. This bracket 14 may be of any suitable form, but as shown comprises a board or plate tiltably mounted, as indicated at 15, upon the sill or some other suitable part of the window frame, the construction being such that the crank or actuating device may be swung toward and from the sash for engagement with or disengagement from the rock shaft, and may also be tilted from a normally horizontal operative position to a vertical or inoperative position, in order to allow the sash to be opened and closed without interference therefrom. Provision is thus made for moving the actuating device into and out of engagement with the rock shaft of the cleaner, and for disposing said actuating device so that it will not interfere with the ordinary opening and closing movements of the window sash.

It will be evident from the foregoing description that my invention provides a cleaner which is adapted for use upon window sashes of various kinds, and particularly upon the window sashes of moving vehicles, or the wind shields of automobiles, whereby the outer surface of the glass may be wiped clear of any frost, rain water or other moisture or foreign substances accumulating thereon, thus allowing the operator

to keep the pane clean for a clear vision. Also it will be seen that by the construction described the cleaner may be operated from the interior of the vehicle in a ready and convenient manner and while the sash is in closed position. 40

Having thus fully described my invention, I claim:

1. In a cleaner for the glass panes of window sashes and the like, the combination of a rock shaft adapted to be mounted upon the window sash, said shaft having a socket at the inner end thereof, an arm carried by the other end of the shaft for movement thereby across the window pane, a wiper carried by said arm, a support hinged to the window frame, and an actuating device adapted for detachable engagement with the socket in the shaft, said device being mounted upon said support so as to be swung into and out of engagement with the rock shaft. 45

2. In a cleaner for the glass panes of window sashes and the like, the combination of a rock shaft adapted to be mounted upon the window sash, an arm carried by said shaft and for movement across the surface of the window pane, a wiper carried by said arm, an actuating device adapted for detachable engagement with the rock shaft, and a support for said device adapted to be mounted upon the window frame and movable in opposite directions for shifting said device into and out of engagement with the shaft. 50 55 60 65 70

In testimony whereof I affix my signature.
WILLIAM R. KUEHNEL.
